United States Patent Office

Des. 180,383
Patented June 4, 1957

180,383

FLUID PUMP

Louis Altman, Racine, Wis., assignor to Vernal F.
Anderson, Racine, Wis.

Application March 28, 1955, Serial No. 35,225

Term of patent 14 years

(Cl. D65—1)

Fig. 2.

Fig. 3.

Fig. 1 is a side elevational view of a fluid pump, showing my new design;

Fig. 2 is an end view taken from the right hand side of Fig. 1; and

Fig. 3 is an end view taken from the left hand side of Fig. 1.

I claim:

The ornamental design for a fluid pump, as shown.
